UNITED STATES PATENT OFFICE.

ARTHUR C. GAYNOR AND EDWIN G. GAYNOR, OF STRATFORD, CONNECTICUT; SAID EDWIN G. GAYNOR ASSIGNOR TO SAID ARTHUR C. GAYNOR.

ELECTRIC SWITCH.

Application filed April 23, 1924, Serial No. 708,390. Renewed December 21, 1926.

This invention relates to an electric switch and, more particularly to a type of switch in which a spring action is utilized to secure a quick making and breaking of contact between the contact terminals.

Among the objects of the invention are, to provide a toggle or switch throwing element for operating the moving contact making blade which is formed of a stamped piece of insulation without inserts or metal pieces, to provide an improved spring device or arrangement giving an effective kick to the moving blade element over a dead point to make or break contact with the contact terminals, to provide a switch or movable blade insulated from all other elements except the contact terminals at the time of contact, to a switch held together entirely by extrusions of metal and without rivets, eyelets, or screws, to a switch having a complete metal barrier between the switch elements and the body of the operator, and to other improvements in the construction of switches of this type.

With these and other objects in view the invention comprises the various features described and set forth in the following specification and claims.

The various features of the invention are illustrated in the accompanying drawings in which;

Fig. 1 is a plan view of a switch embodying a preferred form of the invention.

Fig. 2 is a view in side elevation of the switch shown in Fig. 1.

Fig. 3 is a vertical sectional view of the switch taken on the line 3-3 of Fig. 1.

Fig. 4 is a vertical sectional view of the switch taken on line 4-4 of Fig. 1.

Fig. 5 is a vertical sectional view of the switch taken on line 5-5 of Fig. 4.

Fig. 6 is an enlarged sectional view of the swinging blade and contact terminals of the switch, the position of the toggle or switch throwing element being indicated in dot and dash lines.

Fig. 7 is a view of the swinging contact blade and contact terminals similar to that of Fig. 6 but showing the toggle elements in a position just passing over the dead center of the switch.

Fig. 8 is a view of the switch elements similar to that of Fig. 7 but showing the swinging blade in noncontact or contact breaking position,

Fig. 9 is a view of a support for the swinging blade and toggle elements,

Fig. 10 is a perspective detail view of a rocking element of the toggle switch element,

Fig. 11 is a detail view of contact elements and insulating and supporting elements therefor, and the toggle and moving blade elements shown in positions slightly spaced from their assembled positions,

Fig. 12 is a side view of the fixed contact terminals and their supporting insulating mountings, one of the insulating elements being shown in slightly displaced position,

Fig. 13 is a top or plan view of the elements shown in Fig. 12, one of the insulating elements or plates being shown in proper position in dotted and dash lines and in displaced position in full lines.

Fig. 14 is a view in perspective of the various elements of the switch shown in positions spaced upwardly from the positions which they occupy in assembled position.

In our present invention the metallic or conducting elements of the switch are mounted in a receptacle or enclosing structure of insulating material, preferably one built up of plates or laminae of insulating material held in position by a suitable frame structure.

The moving or swinging elements of the switch are mounted on a stand, which may be of metal, and which is held in position by being fitted between the walls of the enclosing receptacle and also by the aid of protrusions or extrusions of metal anchoring into suitable openings in the insulating plates without the necessity of rivets or other similar joining or anchoring elements.

On this stand or support is pivoted a contact connecting or switch member having rigid arms adapted, in one position, to span and connect a pair of insulated contact terminals mounted in the receptacle and, in another position, to swing free of these contact terminals.

This swinging contact element is actuated, through suitable spring or snap connection, from a rocker also pivoted on the stand or support on an axis spaced from that of the contact element. The spring device is so constructed and mounted between the contact and the rocker elements that, as the rocker is tilted on its pivot, the spring is compressed,

tending to hold the contact in position, un-

til the rocker passes a point within its path of movement and after this point is passed the spring is permitted to expand and throw the contact element to its extreme opposite 5 position. This rocker element is preferably made of metal and, to actuate it, it is provided with a handle of insulating material, fitted on the upper face of the rocker without the necessity of embedding or riveting 10 it and is formed to project through a suitable opening in the front face of the enclosing structure to enable it to be readily operated. The moving or pivoted elements are thus mounted in a unitary manner in a 15 mounting insulated from both contact terminals except at the time during which these contact terminals are to be connected.

Referring more particularly to the accompanying drawings, the switch elements, comprising a pair of insulated contact terminals 16 and 18 and a pivoted contact connecting or switch member 20, are mounted in a box or receptacle 21 made up of plates of insulating material. The contact terminals are 20 mounted and held between a plate 22 forming an outer side wall of the box and a plate 24 forming an inner wall or partition, the terminals having for this purpose portions 26 and 28 bent at an angle to lie against the 25 outer face of the wall 22, portions passing inwardly and fitting in notches 30 and 32 in the ends of the wall, then extending sidewise as at 34 and 36 between the walls 22 and 24 and then extending through notches 38 and 35 40 in the ends of the inner wall 24 and forwardly at 42 and 44 to a position in the box to be touched by the contact connecting member 20, when the latter is in contacting position. As shown in the drawings, it is preferred to have one contact terminal in an 45 upper corner and the other one in the opposite lower end corner. The terminals are bent at right angles at their inner ends to form contact portions 46 and 48 in position 50 to be touched by the ends of the pivoted connecting contact member 20. The face portions 26 and 28, lying on the outer face of the wall 22, are also provided with suitable binding screws 50 and 52 through which electric 55 connections may be made with an outside circuit. The contact terminal members are held in position in the notches in the ends of the walls or plates 22 and 24 by means of end plates 54 and 56 of insulating material 60 lying against the ends of the plates 22 and 24 to form the end walls of the insulating enclosure, the walls 54 and 56 being provided with notches 58 and 60 suitably positioned to receive projecting portions 62 and 64 of 65 the walls 22 and 24 thus holding these walls and the contact terminal members fitted rigidly in position. The walls 22 and 24 are further held in position by means of a plate 66 forming the bottom of the insulating 70 enclosure lying under the wall 24 and

provided with an opening 68 into which fits a lug portion 70 extending downwardly from the lower edge of the wall 24.

The switch member 20 for connecting the contacts 16 and 18 and the actuating mechanism therefor are mounted on a support or frame 72 shown in perspective in Fig. 9 in the enclosing insulating structure and having a side wall 74 extending upwardly adjacent the wall 24 from a base wall 76 supported on the bottom plate 66. The actuating element is mounted on the wall 74 and the switch member is pivoted on a parallel wall 78 extending upwardly from the opposite edge of the base wall 76. The base of 80 the support or frame 72 rests on the bottom plate 66 and the support is further anchored and supported in its proper position by means of a lug 80 projecting from the side wall 74 through an opening 82 in the inner 85 wall plate 24. The support or frame 72 is held against the wall 24 by an outer side wall 84 which, with a cover plate 86 of insulating material, completes the enclosing insulating structure. 90

The switch member 20 is pivoted on a pivot pin 88 stamped from the upper portion of the side wall 78 towards a spaced portion 90 formed by continuing the upper portion of the wall 78 inwardly and horizontally as at 92 for a distance slightly greater than the thickness of the switch member 20 and then extending downwardly to form the portion 90. The switch member 20 is thus pivoted and retained between the side wall 78 and downwardly depending portion 90. A pair of rigid or integral arms 94 and 96 are formed on the switch member 20 to extend at such angles from each other that their ends, in one position of this member, touch or contact with the contact portions 46 and 48 of the contact terminals 16 and 18 positioned at opposite corners of the insulating enclosure as shown in Figs. 4, 6 and 7, one arm 96, in this position resting against the under 100 side of the upper horizontal portion 92. When the contacts connecting member is tilted to bring the other arm 94 against the under face of the portion 92, the arms 94 and 96 are swung to bring their ends to the opposite corners of the insulating enclosure and at the maximum distance from the contact faces 46 and 48, as indicated in Fig. 8. The switch member 20 is preferably formed of a pair of plates or laminae 98 and 100 placed 105 side by side and having their contact ends slightly spread to tightly enclose the contact portions 46 and 48 of the contact terminals. The edges of the contact portions 46 and 48 are beveled as at 102 to prevent or minimize the danger of the switch member striking the edge of the portions and thus failing to make an effective contact. 110

The switch member 20 is also provided with a downwardly depending arm 104 in 115

an equi-angular position to the arms 94 and 96 through which an actuating movement or impulse may be received from a spring 106 preferably of a flat coil type having one end 107 connected to the lower portion of the arm 104 and connected at its other end to an operating mechanism. To provide a secure anchorage for the end of the spring 106 the laminæ or plates 98 and 100 are separated at the lower end of the arm 104, the end of the plate 98 being bent about the end of the plate 100 as shown in Fig. 5.

A rocker member 108 from which the impulse is given to the spring 106 is mounted on a pivot 110 pressed inwardly from the wall 74 of the supporting frame and is retained in position between the wall 74 and a lug 112 punched up from the bottom wall 78 of supporting frame in spaced position from the wall 74. The end 113 of the spring 106 is attached to the rocker member 108 at some distance above the pivot 110, the rocker 108 being provided for this purpose with an upwardly projecting arm 114, 25 slightly offset towards the spring and switch member and provided in its upper portion with a perforation 116 to receive the end of the spring.

When the switch member 20 swings from one limit of its movement to the other on the pivot 90 the end 107 of the spring 106 attached to the arm 104 of the swinging member swings from one side of the pivot 110 of the rocker 108 in an arc passing beneath this pivot. Similarly, when the rocker member swings on the pivot 110, the end 113 of the spring swings from side to side of the pivot 90 on an arc passing above this pivot. The spring 106 tends to expand and, as any tendency for the arm 104, of the switch member 20, to swing from one position to the other about the pivot 90 tends to swing the end 107 of the spring nearer to the end 113, the spring 106 tends to keep the switch member 20 in one limit or the other of its limit of movement corresponding to the position of the rocker 108. Thus, when the switch member and the rocker member are in the position shown in Fig. 6 a swinging of the end 107 of the spring to the left about the pivot 90 would compress the spring 106.

As the rocker arm 108 is tilted on the pivot 110 to the right from the position of Fig. 6, the end 113 of the spring 106 also swings about the pivot 110 and is brought closer to the end 107 thus compressing the spring and tending to hold the member 20 in position. This compression continues with the movement of the rocker arm until a position of maximum compression is reached at a point on the center line of the pivots 90 and 110 between the limits of movement of the rocker arm, as indicated approximately in Fig. 7. After this point is passed, a tilting of the arm 20 to the position shown in Fig. 8

would be accompanied by an expansion of the spring, and, accordingly, the spring tends to expand and throw the arm to the position shown in Fig. 8, the energy stored up in the previous compression of the spring 106 serving to throw the switch member 20 to this position with a strong, positive kick.

The rocker member 108 is operated by means of a handle member 118 of insulating material having a portion projecting through a slot 120 in the cover 86. The lower edge of the handle member 118 is straight at 124 at each end to rest on corresponding straight faces 126 on the upper edge of the rocker member and the handle member 118 is held in position on the rocker member by extending the end 113 of the spring 106 through a suitably placed opening in the handle member. The handle member 118 is held in position on the rocker member against sidewise displacement by being inserted between the offset arm 114 and the wall 24. To further position and secure the insulating handle in position on the rocker the rocker is provided with an upstanding lug 128 fitting into a notch 130 in the lower edge of the handle member and being turned at an angle as 132. When the various parts of the apparatus are assembled the handle element will be held in position without the necessity of any further holding means.

The various walls of the insulating enclosure are held in position by means of a metallic frame 134 and a metallic cover plate 136. The frame 134 is formed with a bottom plate 138 on which the insulating plate 66 rests, end plates 140 and 142 against which the end insulating plates 54 and 56 are positioned and a back plate 144 against which the side plate 84 is held. A lug 146 projecting upwardly from the front edge of the bottom plate serves to hold the plate 22 in position. The top plate 136 is turned downwardly at its edges to form a downwardly depending flange 148 which encloses the upper edges of the walls 140, 142 and 144, and is held in position by means of lugs 150 and 152 which project through openings 154 and 156 at the edges of the cover and are turned downwardly against endwise projecting arms 158 and 160 of the cover plate. The arms 158 and 160 are provided with suitable openings 162 and 164 for securing the device in position. An opening 166 is also provided in the cover in alignment with the opening 120 in the cover plate 86 to permit the handle member 118 to project out of the receptacle in position to be grasped by an operator. The upper edge of the handle member is rounded as at 168 to closely fit the openings 120 and 166 in all positions of the handle.

In assembling the apparatus, the switch member 20 and the rocker 108 are pivotally secured in the frame 72 and the other mem-

bers of the device are then fitted in their proper places and inserted into the frame 184. The interfitting of the various members then serves to hold them in their proper positions without further securing means. In assembling the various elements of the device, the plates 22 and 24 and the contact terminals 16 and 18 are fitted into position as indicated in Figs. 11, 12 and 13, and the 10 end pieces then fitted to the ends of the plates 22 and 24 to hold them in position. The handle member 118 is then fitted onto the rocker 108 and the lug 80 of the frame 72 fitted into the opening 82 in the plate 24. 15 The structure thus assembled is placed in the relation shown in Fig. 14 the lug 70 of the plate 22 being fitted into the opening 68 in the bottom plate 66, the plate 84 being placed in position against the inner face of the wall 144 of the frame 134 and these elements being then pressed into position in the frame. The cover plates 86 and 136 are then placed on the frame the lugs 150 and 152 projecting through the openings 154 and 156 and then 20 25 clinched into place.

As changes of construction could be made within the scope of our invention it is intended that all matter contained in the above description or shown in the accompanying drawings shall be interpreted as illustrative and not in a limiting sense.

Having thus described our invention what we claim as new and desire to secure by Letters Patent is:

55 1. A device of the type described which comprises, an enclosure having a pair of spaced walls of insulating material, said walls having notches at their ends, one of said walls forming an outer wall of said enclosure, a pair of contact terminals, one at each end of said enclosure, each terminal having a portion fitted between the end portions of said plates and extending through said notches to the outer face of said outer wall and to the interior of said enclosure. 40 45

2. A device of the type described which comprises, an enclosure having a pair of spaced walls of insulating material, said walls having notches at their ends, one of said walls forming the outer wall of the enclosure, the notch at one end of the inner place being at the upper edge corner and the notch at the other end being at the lower edge corner, a pair of contact terminals 50 55 one at each end of said enclosure, each terminal having a portion fitted between the end portions of said spaced walls and extending through said notches to the outer face of the outer wall and through the notches at the corners of said inner wall to the interior of said enclosure. 60 65

3. A device of the type described which comprises, a pair of spaced walls of insulating material, one of said walls forming an outer wall of said enclosure, said walls hav-

ing notches in their ends, a pair of contact terminals one at each end of said enclosure, each terminal having a portion fitted between the end portions of said walls, and extending through and lying flat against the outer face of said outer wall and extending inwardly through the notches of said inner wall to the interior of said enclosure. 70 75

4. A device of the type described which comprises, a pair of spaced walls of insulating material, one of said walls forming an outer wall of said enclosure, said walls having notches in their ends, a pair of contact terminals one at each end of said enclosure, each terminal having a portion fitted between the end portions of said walls, extending through the notches of said outer wall and through the notches of said inner wall to the interior of said enclosure, and end walls having spaced notches to receive the end portions of said spaced walls. 80 85

5. A device of the type described which comprises, a pair of spaced walls of insulating material, one of said walls forming an outer wall of said enclosure, said walls having notches in their ends, a pair of contact terminals, one at each end of said enclosure, each terminal having a portion fitted between the end portions of said walls, and extending through the notches of said outer wall and through the notches of said inner wall to the interior of said enclosure, end walls having spaced notches to receive the end portions of said spaced walls, and a metallic holding frame retaining said walls in position. 90 95

6. A device of the type described which comprises, a pair of spaced walls of insulating material, one of said walls forming an outer wall of said enclosure, said walls having notches in their ends, a pair of contact terminals, one at each end of said enclosure, each terminal having a portion fitted between the end portions of said walls, and extending through the notches of said outer wall and through the notches of said inner wall to the interior of said enclosure, said inwardly extending portions lying one at the upper portion and one at the lower portion of their respective ends of the enclosure, and a pivoted switch member having arms connecting said contact terminals in one position and tilttable to a position disconnected from both of said terminals. 100 105 110 115

7. A device of the type described which comprises, an insulating enclosure, a pair of contact terminals therein, a switch member, a stand on which said switch member is pivoted in operative relation to said contact terminals, a wall of insulating material in said enclosure, said wall having an opening therein, said stand fitting into said insulating enclosure against said wall, and a lug on said stand fitting into said opening in said wall. 120 125 130

8. A device of the type described which comprises, an insulating enclosure formed of walls fitted to each other and held in a metal frame, a pair of contact terminals therein, 5 a switch member, a stand on which said switch member is pivoted in operative relation to said contact terminals, a wall of insulating material in said enclosure, said wall having an opening therein, said stand fitting 10 into said insulating enclosure against said wall, and a lug on said stand fitting into said opening in said wall.
9. A device of the type described which comprises, an enclosure formed of walls of 15 insulating plates fitted to each other and held in a metal frame, an inner wall of insulating material spaced from one of the outer side walls and having an opening in its inner face and notches in its ends, a 20 pair of contact terminals one at each end of said enclosure, each terminal having a portion fitted between said inner wall and the proximate outer wall and extending through said notches into the interior of said enclosure, a switch member, a stand on which said switch member is pivoted in operative 25 relation to said contact terminals, said stand fitting into said enclosure against the inner face of said inner wall, and a lug on said stand fitting into the opening in said inner wall.
10. A device of the type described which comprises, a stand having spaced upright walls, a pivot on one wall, a switch member 30 on said pivot, said wall being bent downwardly to enclose said switch member, a rocker member pivoted on the inner face of the opposite wall, an upright lug struck up from the bottom of said stand to enclose said 35 rocker member and a spring between and connected to said rocker member and said spring.
11. A device of the type described which comprises, a stand having a pair of spaced 40 upright walls, a pivot on one wall, a switch member on said pivot, said switch member having a pair of switch arms extending sideways from said stand and a downwardly depending arm therebetween, a rocker member 45 pivoted on the inner face of the opposite wall, a spring between and connected at its 50 ends to said rocker and said switch members, and means on said walls to retain said rocker and switch members on said pivots.
12. A device of the type described which 55 comprises, a stand having a pair of spaced upright walls, a pivot on one wall, a switch member on said pivot, said switch member having a pair of switch arms extending through opposite ends of said stand and a 60 downwardly extending arm depending therebetween, a rocker member pivoted on the inner face of the opposite wall, a spring between and connected to said rocker and switch members and stops on the upper part 65 of said wall on which said switch is mounted against which said switch arms may abut.
13. A device of the type described which comprises, a supporting wall, a rocker pivoted on one side of said wall, an offset arm 70 projecting upwardly from said rocker, a handle of insulating material fitted to rest against the upper edge of said rocker, said handle member being contained between said offset arm and said supporting wall, and a 75 pin extending from said arm into an opening in said handle member.
14. A device of the type described which comprises, an enclosure of insulating material having a pair of spaced walls, one of 80 said walls forming an outer wall and the other an inner wall of said enclosure, said walls having notches in, and lugs projecting from, their ends, a pair of contact terminals one at each end of said enclosure, each terminal having a portion held between said walls and a portion projecting through said 85 notches into the interior of said enclosure, end walls having notches receiving said lugs, a bottom wall having an opening, a lug depending from said inner wall into said opening, a support having a lug projecting therefrom into an opening in said inner wall, an outer wall holding said support in position 90 against said inner wall, a frame holding said walls in position, and a switch member and actuating means therefor mounted in said stand to swing into contact with said contact terminals.

ARTHUR C. GAYNOR.

ED G. GAYNOR.
